ABSTRACT: In a clamping arrangement for clamping a feedstock billet extending into a high pressure chamber against axial forces which act along the length of the billet and are sufficiently large to develop stresses greater than the yield stress of the billet material, a portion of the feedstock billet is clamped between clamping members. The clamping members are separated from the interior of the high pressure container by a passage capable of passing the billet when the chamber is not under pressure. When the pressure in the chamber is high, relative deformation occurs between the passage wall and the billet to provide frictional engagement over a length sufficient to reduce the stress in the billet to a value below its yield strength in the region adjacent the clamping members.

FEEDSTOCK CLAMPING MEANS

The present invention relates to clamping means for clamping feedstock billets against axial forces acting along the length of the billets and sufficiently large to develop stresses greater than the yield stress of the billet material. Such clamping means are required for example in the cyclic hydrostatic extrusion of billets. Each cycle of such an extrusion process comprises the steps of advancing the continuous billet into a chamber, clamping the billet, applying a very high pressure to the interior of the chamber a portion of the billet is extruded through an extrusion die and thereafter reducing or removing the pressure to enable the billet to be once more advanced into the chamber, the extrusion produced remaining in one piece with the billet.

The cyclic hydrostatic extrusion process requires means for clamping a length of billet or feedstock in a region where it passes through a wall of a container capable of withstanding a high hydrostatic pressure. In the course of a cycle of cyclic hydrostatic extrusion, the clamping means must be capable of securely holding the feedstock billet against a large end force exerted on it from within the container and thereafter must be easily freed to enable a length of the feedstock billet to pass through the clamping means into the container. Moreover it is desirable that the clamping means should be capable of accommodating a comparatively large tolerance range of feedstock billet tolerances so that the apparatus may be used for cyclic extrusion of hot-rolled or cast billets. It is further desired that the feedstock billet should not be appreciably marked as the result of the clamping operation.

In accordance with this aspect of the present invention, there is provided a clamping means for a feedstock billet to hold the billet against a large end force, the said clamping means comprising a rigid-walled passage permitting the passage therethrough of feedstock billet up to the maximum required tolerance limit, and means for releasably holding the billet at the back end of the passage, that is at the end remote from the force, while the billet deforms into frictional contact with the passage wall.

When such clamping means are used in cyclic hydrostatic extrusion, increasingly high hydrostatic pressure within the container deforms the billet into frictional contact with the wall of the passage. The greater the pressure within the container, the greater will be the end force tending to deform the billet, and hence the greater will be the frictional contact between the billet and the wall of the passage.

The deformation of the feedstock billet in the passage is in general caused by buckling and upsetting. This occurs preferentially at the forward end of the passage so that the force applied to the holding means at the rear end of the passage does not appreciably exceed the yield stress of the feedstock billet material.

When the pressure in the container is reduced, the deformed portion of the feedstock billet will usually have sufficient resilience to free itself from the wall of the passage so that a further length of feedstock billet may be fed into the container without binding. However, in order to facilitate this operation, it is preferred to form the passage by means of clamping passage members, also referred to hereinafter as a sizing-tube, the interior of which has the required cross section to form the said passage, the sizing-tube being formed of a number of segments which can be moved outwards away from the axis of the passage to free the feedstock billet. The sizing-tube segments may be forced together to define the passage by mechanical or hydraulic means. Where the surface of the billet is defined by a number of planes, the sizing-tube may be divided along these planes so that each segment may slide relative to its neighbor into contact with the billet without affecting the movement of the neighboring segment. This is particularly advantageous where the feedstock billet is in the form of a cast ingot, such ingots tending to vary considerably in their cross-sectional dimensions. In some cases the contact between the deformed feedstock billet and the wall of the sizing-tube could be so complete around the forward end of the sizing-

tube as to avoid the need for any additional seal to prevent the escape of fluid under pressure from the container.

The shape of the exterior of the sizing-tube may be cylindrical or tapered or any other desired circular or noncircular shape.

In accordance with a further aspect of the present invention there is provided a clamping means for a feedstock billet passing through a wall of a high pressure container, the said clamping means comprising a deformable-walled passage which in its relaxed state permits the passage of billet material therethrough, the rear end of the passage being supported while the front end of the passage is subjected to the fluid pressure in the container, the arrangement being such that the container pressure deforms the passage wall into gripping contact with the feedstock billet. Such an arrangement is particularly advantageous where the feedstock billet material is brittle. It may also avoid the need for a seal to prevent the escape of fluid from the container between the feedstock billet and the passage wall.

Embodiments of these and other aspects of the present invention and their application to cyclic hydrostatic extrusion apparatus will now be described by way of example with reference to the accompanying drawings, in which:

FIG. 1 shows in side elevation a length of feedstock billet which has been clamped between three clamping jaws, the right hand end of the feedstock billet having been subjected to high hydrostatic pressure,

FIG. 2 shows one form of clamping means in axial section,

FIG. 3 is a view similar to FIG. 2 of an experiment to determine the behavior of an unsupported length between the sizing-tube and the holding means.

FIG. 4a through 4h show in cross section a number of arrangements forming the sizing-tube segments,

FIG. 5 is a longitudinal sectional view of an alternative clamping arrangement employing a resiliently deformable sizing-tube, the sizing-tube being shown in its relaxed state,

FIG. 6 is a view corresponding to FIG. 5 showing the clamping arrangement in operation under high pressure, and

FIG. 7 is an axial section of another embodiment of the feedstock clamping means of the present invention.

The length of feedstock billet shown in FIG. 1 has been clamped between three clamping jaws in the form of 120° segments which together make up a complete cylinder extending over a length l_0 . The right hand end of the specimen was then subjected to a high hydrostatic pressure in excess of the yield stress of the material of the specimen, in this case commercially pure aluminum. This caused the material to deform into close contact with the surfaces of the clamping members and in particular resulted in the formation of flashes 2 on the surface of the specimen 1 where the billet material was forced into the crevices between adjacent clamping members. It will be noted that the flashes 2 are of greatest height at the right hand end of the clamped portion and extend altogether over a length l_1 which is appreciably less than the total clamp length l_0 . From this it is deduced that the deformation of the billet material is greatest at the right hand end, that is at the end nearest the high hydrostatic pressure, and that the deformation diminishes progressively with distance away from this region until a region 3 is reached where there is no deformation of the material. This indicates that to the left of the region 3, the clamped portion of length $l_0 - l_1$ is subjected to an end pressure less than the yield stress of the material.

In order to prevent marking of the feedstock billet by the clamping means, it is apparent that in the region 1, the clamping means must present the desired smooth continuous support surface against which the billet material can be deformed. In the region $l_0 - l_1$, to the left of the region 3, the necessary clamping pressure does not exceed the yield stress so that the feedstock billet can be adequately held here without marking it.

FIG. 2 shows an embodiment of clamping means based on this hypothesis. In the arrangement shown in FIG. 2, a length 75 of feedstock billet 1 is clamped by means of a set of jaws 4

similar to those which had been used on the specimen shown in FIG. 1, the clamping pressure of the billet being however less than the yield stress of the billet material. The right hand end of the billet 1 passes through an opening 5 in a high pressure container 6 in which a high hydrostatic pressure greater than the yield stress of the billet material can be generated. A sizing-tube 7 of length l_1 has a cylindrical bore 8 in which the billet 1 is a loose fit. A high pressure fluid seal 9 is located in a recess in the front end of the sizing-tube 7 adjacent the wall of the container 6. The combined length of the clamp formed by the members 4 and the sizing tube 7 is l_0 , corresponding to the required total length l_0 in the specimen as shown in FIG. 1 to provide the necessary frictional force to hold the feedstock billet.

In operation, the clamping means 4 are applied against the feedstock billet and the pressure inside the container 6 is then progressively raised. When this pressure reaches the yield stress of the billet material, the latter begins to deform initially in the region of the seal 9 to contact the wall of the bore 8. As the contact between the billet material of the bore wall is inevitably frictional, an additional frictional holding force will be available to resist movement of the feedstock billet 1. As the pressure in the container rises further, the region of deformation of the billet material will extend progressively to the left of the seal 9. Since the spread of deformation of the material requires movement of the material nearer to the seal 9, it is obvious that the stresses and also the sizing-tube/billet interface pressure will be greatest adjacent the seal and will steadily diminish with increasing distance to the left of the seal 9. By appropriate choice of the length l_1 in relation to the maximum pressure in the container 6, the radial compressive stress at the rear or left hand end of the sizing-tube 8 may be equal to or even less than the yield stress of the billet material even when the pressure within the container is considerably greater than the yield stress. Consequently the holding means 4 do not need to exert a pressure on the feedstock billet which is greater than the yield stress of the billet material so that appreciable marking by the jaws 4 or by extrusion between the jaws 4 is unnecessary.

FIG. 3 shows an experiment conducted to confirm the operation of the clamping means shown in FIG. 2. In this experiment, a length of feedstock billet 11 is mounted in a 6-inch long hardened steel tube 12 having a 5/16-inch reamed bore, the tube 12 being tapered on the outside and split into two halves along an axial plane. The two halves are held together by forcing an outer sleeve 13 having a correspondingly tapered bore over the tube 12 with a substantial preload which ensures that no gap can occur at the interface between the two tube halves when a radial pressure of 40 tons per inch square acts in the bore. The billet 11 was of commercially pure aluminum and was able to slide freely in the bore before pressure was applied. A 1 1/4-inch projection 14 at the rear end of the tube 12 was enclosed in a spacer 15, the bore in the spacer being relieved to 3/8-inch diameter for most of its length to provide a clearance 16 between it and the billet 11. The back end-face of the billet 11 was abutted against a stop-bar 17 secured by tie rods 18 to a high pressure container 19 into which the forward end of the billet 11 projected through a seal 20.

Tests were carried out with a number of billets. First a billet with an initial diametral clearance of only 0.0005 inch was placed into the tube and pressure applied in increments of 5 tons/in² up to 40 tons/in². After each pressure application the specimen was examined and it was found that, at the maximum pressure, the diameter of the unsupported part 14 of the billet increased to a size 0.002 inch larger than the bore of the sizing tube. In one test, after reaching the 25 tons/in² stage, the container was depressurized and a thin washer was inserted into the endstop assembly, to provide a 0.03-inch air space at the end of the billet. On the reapplication of pressure the billet retracted smoothly until the end stop was contacted once more, indicating the continued need for some slight axial restraint. The unsupported length 14 of the specimen slightly buckled when the initial clearance was increased to 0.004 inch

and the unsupported diameter increased as before to a size 0.002 inch above the sizing-tube diameter. These experiments indicate that, if the holding means is closely adjacent to the sizing tube, full control of the feedstock is possible without clamping marks of any importance remaining on the billet surface.

In order to facilitate the release of the billet from the sizing-tube after release of the end force, for example on depressurizing of the hydrostatic pressure container, it is desirable 10 that the sizing-tube should be split into two or more segments as in the case of the sizing-tube 12 shown in FIG. 3. FIGS. 4a to 4h show in cross section a number of possible arrangements of the sizing-tube segments. In FIG. 4a, the billet 1 is of circular section and the sizing-tube is divided into three equal segments. FIGS. 4b to 4d show three alternative methods of holding a square section billet, the sizing-tube being divided into segments by planes coincident with the boundary planes of the billet. FIG. 4e shows a modification of FIG. 4d for use with a square section billet having rounded edges. FIGS. 4f to 4h show arrangements for the sizing-tube segments for use in holding billets of other cross sections, the planes of division between the sizing-tube segments coinciding with the plane surfaces of the billet.

When individual straight bars of feedstock are loaded in 25 succession into the machine, the function of the sizing-tube will permit the abutting end-faces of adjacent billets to be unprepared in respect of flatness and squareness. Badly matched end-faces will be fully merged as the joint passes through the 'compression zone' of the sizing-tube.

30 In view of the comparatively small holding force required to be applied by the holding means, it may be sufficient in some cases for the sizing-tube additionally to perform the function of the holding means. For this purpose the arrangement shown in FIGS. 4d to 4g are appropriate since each sizing-tube segment can be applied by a force in the direction of the arrow shown without interfering with the proper movement of its neighbors. Such arrangements also enable the separate seal to be dispensed with. Moreover the independent movement of 40 each segment enables the sizing-tube to accommodate the full range of tolerances for the billet.

The sizing-tube segments may be actuated by the pressure within the container or by other externally operated means.

The arrangement shown in FIGS. 5 and 6 comprises a high 45 pressure container 21 having an inlet opening 22 for the feedstock billet 23. Mounted in the container 21 adjacent the opening 22 is a resiliently deformable sizing-tube 24 which in the relaxed state may have the shape shown in FIG. 5.

External holding means 25 hold the billet 23 against the initial end force which may be exerted on the billet 23 as the pressure within the container 21 begins to rise. As this occurs, the sizing-tube 24 is deformed into sealing contact with the billet 23. The rising fluid pressure causes axial compression with the sizing-tube starting from the right hand end, that is 55 the end in contact with the fluid. This causes a radial pressure inwards against the billet to oppose radial extension of the billet and to grip the latter frictionally. As the container pressure rises, a pressure gradient is set up along the feedstock surface. Even when the full pressure within the container is reached, for example a pressure sufficient to cause extrusion of the billet through a die (not shown) the pressure gradient along the feedstock surface diminishes from the full container pressure at the right hand end to a value below the billet material yield stress in the region of the opening 22.

60 If desired, the sizing-tube 24 may in its relaxed state have the shape shown in FIG. 6, passage of the billet 23 through it being effected by allowing the tube 24 to deform to the shape shown in FIG. 5 as a result of frictional contact between the moving billet and the tube.

65 The resilient sizing-tube may be of composite construction of more than one material for example it may be laminated and it may have a conical or other noncylindrical outer shape. The resilient material may include suitable rigid reinforcements and may be loaded with suitable filling materials to obtain the characteristics required to suit the billet material.

FIG. 7 shows in axial section another embodiment of feedstock clamping means employing a segmented rigid sizing tube 31. The sizing-tube has a cylindrical external surface around which snugly fits a rubber sleeve 32. Pressure is applied around the outside of the sleeve 32, this pressure for example being that generated within the high pressure container, and this pressure holds the segments of the sizing-tube in the closed position.

The holding means comprise a set of clamping jaws 33 which are applied against the feedstock billet 34 by force of diametrically opposed plungers 35 operated by any convenient source of fluid pressure.

We claim:

1. Clamping means for clamping a feedstock billet against forces applied to said billet in the axial direction thereof by high pressure in a chamber, said chamber having an opening through which said billet can extend, said clamping means comprising: clamping members including means for gripping said billet with a pressure sufficient to frictionally clamp the billet but insufficient to substantially mark said billet; clamping passage members together defining a clamping passage through which said billet is slid able, said clamping passage members being separable to increase the effective cross-sectional area of said passage; means for forcibly holding said clamping passage members together and sealing means separating said clamping passage from said chamber opening,

said sealing means being arranged to seal against said billet to prevent fluid from said chamber entering said clamping passage; said clamping passage having a length sufficient to reduce the stress in the billet to a value below its yield strength in the region of the billet adjacent the gripping members.

2. Clamping means according to claim 1, in which said clamping passage members are bounded by axial planes of separation between adjusting clamping passage members.

3. Clamping means according to claim 1, in which a flexible tube surrounds said clamping passage members and means are provided for applying fluid pressure from said chamber around said flexible tube.

4. Clamping means according to claim 1, in which said clamping passage members are bounded by axial planes of separation between adjacent clamping passage members in which a flexible tube surrounds said clamping passage members and means are provided for applying around said flexible tube the fluid pressure in said chamber.

5. Clamping means according to claim 1, in which said clamping passage members are segments of a sizing tube, the external surface of said sizing tube being a surface of revolution.

6. Clamping means according to claim 5, in which said external surface of said sizing tube is tapered to cooperate with a corresponding internally tapered sleeve.
